UNITED STATES PATENT OFFICE.

FREDERIK G. WHITTINGTON, OF CHICAGO, ILLINOIS, ASSIGNOR TO STEWART-WARNER SPEEDOMETER CORPORATION, OF CHICAGO, ILLINOIS, A CORPORATION OF VIRGINIA.

DESIGN FOR A RADIATOR-CAP.

58,848.

Specification for Design.

Patented Aug. 30, 1921.

Application filed May 9, 1921. Serial No. 468,171. Term of patent 7 years.

To all whom it may concern:

Be it known that I, FREDERIK G. WHITTINGTON, a citizen of the United States, residing in the city of Chicago, county of Cook, and the State of Illinois, have invented a new, original, and ornamental Design for a Radiator-Cap, of which the following is a specification, reference being had to the accompanying drawings, forming a part thereof.

In the drawings:

Figure 1 is a top plan view of a radiator cap in accordance with my design.

Fig. 2 is a perspective view of a radiator cap embodying said design.

Fig. 3 is a front elevation of the same.

Fig. 4 is an end elevation of said cap.

I claim:

The ornamental design for a radiator cap as shown.

In testimony whereof, I have hereunto set my hand at Chicago, Illinois, this 26th day of April, A. D. 1921.

FREDERIK G. WHITTINGTON.
